COAL PUSHER

Eugene Martin, Wesleyville, Pa., assignor to The Standard Stoker Company, Incorporated, a corporation of Delaware

Application May 22, 1945, Serial No. 595,129

2 Claims. (Cl. 105—233)

1

The invention relates to power operated appliances, known as coal pushers, for pushing coal from the rear to the forward portion of the coal bin of a locomotive tender to place it within convenient reach of the fireman, or to move the coal forward to the conveyor trough of a stoker if the tender is so equipped.

In apparatus of this type it has been usual to provide transversely extending longitudinally spaced pusher heads operatively linked together, the rearmost pusher head being connected by means of a piston rod with the piston head of a steam cylinder of a reciprocating motor. In such constructions it has been customary to provide a stationary shield or hood forward of the cylinder within which the piston rod may work, as a result of which, rearward movement of the rearmost pusher head is restricted to the forward end of the shield or hood, thereby limiting the area of pushing effectiveness of the coal pusher.

It is, therefore, an object of this invention to provide improved means for advancing fuel in a tender fuel bin, and more particularly to provide a coal pusher construction in which the pusher heads are effective, for pushing coal, over a greater area per unit of space occupied by the coal pusher than in previous constructions. More specifically the invention contemplates a construction in which the rearmost pusher head may move a greater distance rearward in the coal bin while maintaining the cylinder in substantially the same relative position in the coal bin as in previous constructions, thereby increasing the effective area of operation of the coal pusher.

It is also an object of the invention to provide a pusher construction in which the rearmost pusher head in its retracted position can be moved rearwardly to a position adjacent the cylinder, while providing protection for the piston rod against contact with the coal in the bin when the pusher head is moved to its foremost position.

Additional objects, advantages and features of invention reside in the construction, arrangement and combination of parts, as will be understood from the preferred and practical embodiment of the invention hereinafter described and illustrated in the accompanying drawings, in which

Figure 1 is a longitudinal vertical section through a portion of a tender coal bin with the improved coal pusher applied thereto and shown in elevation;

Figure 2 is a plan view corresponding to Figure 1;

Figure 3 is an enlarged sectional view taken on the line 3—3 of Figure 2;

2

Figure 4 is a fragmentary sectional view taken on the line 4—4 of Figure 3, parts being shown in elevation; and

Figure 5 is a sectional view taken on the irregular line 5—5 of Figure 3.

The invention has been shown in the drawings and will be described as applied to a locomotive tender bin, however, it is evident that the invention may be used to advantage in other types of bins and for movement of materials other than coal.

In the drawings, the numeral 10 indicates a tender fuel bin including the sloping side walls 11 and 12, the rear slope sheet 13 provided with a wear plate 14, and the rear wall 15.

The coal pushing device, generally indicated at A, is mounted on the rear slope sheet 13 and includes a plurality of pusher heads, three being shown in the drawings indicated respectively by the numerals 16, 17 and 18. The pusher heads are in the form of transverse bars, substantially wedge-shaped in longitudinal vertical cross section providing the upstanding pusher faces 19, 20 and 21. The bottom sides of the pusher heads rest on the wear plate 14 over which they are adapted to reciprocate.

In the drawings the pusher heads are shown in their retracted or rearmost position. When the pusher heads are advanced to their foremost position, the pusher head 18 travels a short distance along the horizontal floor portion 22 of the fuel bin. In order to permit movement of the pusher head 18 in a horizontal plane while the pusher head 16 is moving in a plane parallel with the slope sheet 13, the pusher heads 16 and 18 are articulated together by means of connecting rods 23, the rods 23 being flexibly connected at their ends with the pusher heads 16 and 18. The intermediate pusher member 17, which is rigidly secured to the connecting rods 23, will raise slightly from the surface of the slope sheet 13 when the pusher member 18 travels over the horizontal floor portion 22, but since this is only a small distance, the extent that the pusher head 17 raises, is not objectionable.

If it is desirable to push coal farther forward across the floor of the tender, an additional pusher member can be linked flexibly to the forward end of the pusher head 18. In order to prevent lateral movement of the lower end of the pusher member, the bottom side of the pusher head 18 is slotted to receive the guide rails 24.

The pusher head 16 is connected by means of the piston rod 25 with the piston head 26 of a reciprocating motor, generally indicated as at 27.

The motor 27 comprises in addition to the piston head 26, a cylinder 28 and removable rear and front cylinder heads 29 and 30, respectively. The cylinder 28 is mounted on the upper and rear part of the slope sheet 13 and projects rearwardly through the rear wall 15 of the bin 10, the projecting portion of the cylinder being mounted on the brackets 31. As best shown in Figures 3 and 5, the cylinder 28 extends below the plane of the slope sheet 13, the upper and rear part of the slope sheet 13 and wear plate 14 being recessed as at 81 to accommodate lower portion of the cylinder 28.

In order to mount the cylinder 28, it is provided on each lower side with a plurality of outwardly extending lugs or ears 32 overlying the marginal edges of the wear plate 14 and slope sheet 13 that define the sides of the recess 81. Between the lugs 32 and the wear plate 14 are longitudinally extending laterally projecting guide plates 33, for a purpose to be explained later, the guide plates 33 being spaced from the wear plate 14 by the filler plates 34. Bolts 35 passing through the lugs 32, the guide plates 33, the filler plates 34, wear plate 14 and slope sheet 13, secure the cylinder and the named parts in rigid relation. In the same manner the portion of the cylinder projecting rearward through the rear wall 15 of the bin 10 is secured to the brackets 31.

A hood or shroud 36, arcuate in transverse cross section extends rearwardly from the pusher head 16 and reciprocates therewith. In the drawings the hood 36 is shown integrally formed with the pusher 16, but it is apparent that it may be made as a separable member, secured in any suitable manner to the pusher head 16. The lower interior side walls of the hood 36 are provided with a plurality of lugs forming a guideway 37 receiving the guide plate 33.

On the forward stroke of the pusher heads, it will be seen that the hood 36 forms a shield over the portion of the piston rod 25 projecting forwardly of the cylinder 28, protecting it from the coal in the bin 10. On the rearward stroke of the pusher heads, the hood 36 slides rearwardly over the cylinder 28, the rearward end of the hood projecting through the opening in the rear wall 15, previously referred to as accommodating the cylinder 28.

In order to prevent fine particles of coal from entering between the cylinder 28 and the hood 36 during reciprocating movement of the coal pusher, an arcuate plate 38, attached to and extending forwardly from the rear wall 15, surrounds the hood 36. A removable cover 39 is provided adjacent the forward end of the hood 36 over the connection between the piston rod 25 and the pusher head 16.

The motor 27 is operated by a fluid, preferably steam, the passage of which from the locomotive boiler or any other suitable source of supply is controlled by a valve mechanism, not shown. From this control valve steam passes to the motor 27 through the pipes 40 and 41 which serve alternately as both intake and exhaust lines to their respective sides of the motor piston 26.

The cylinder 28 is provided adjacent its rearward end with a tapped opening 42 to receive the pipe 40, the opening 42 communicating with a cored passage 43, one end of which passage opens through an elongated port 73 into the cylinder 28 a short distance from cylinder head 29, the distance being not greater than the thickness of the piston 26, and the other end of which passage communicates with a cored passage 44,

45 in the cylinder head 29. The passage 44, 45 forms an initial steam intake passage for the cylinder 28, the spring seated valve 46 in the passage shutting off the flow of exhaust steam from the cylinder.

5 At the forward end of cylinder 28, the cylinder head 30 has a tapped opening 47 to receive the pipe 41, the opening 47 communicating with a cored passage 48, 49. The branch 48 of passage 10 48, 49 communicates with the cylinder passage 50, which opens through an elongated port 74 into the cylinder 28 a distance rearward of the cylinder head 30 not greater than the thickness of the piston 26. The passage 48, 49 forms a steam intake passage for the cylinder 28, the spring seated valve 51 in the passage shutting off the flow of exhaust steam from the cylinder.

In the drawings, referring particularly to Figures 3 and 4, the coal pusher is in its retracted position, and if now it is desired to operate the pusher to advance coal in the bin, an operating valve (not shown) of any suitable design, as shown for example in United States Letters Patent No. 1,747,899, issued to Francis Hogg on date 20 of February 18, 1930, is operated to admit steam into the pipe 40. Steam from the supply pipe 40 enters the passage 43, passes into passage 44, raises the valve 46 to pass into the passage 45 and thence into the cylinder 28, the expansion 25 of the steam moving the piston 26 to the opposite end of the cylinder. As the piston 26 moves by and opens the passage 43 to the cylinder, steam will enter the cylinder through the port 73 and since the cross sectional area of the port 73 30 is substantially equal to the cross sectional area of the supply pipe 40 and passages 43, 44 and 45, pressure on both sides of spring seated valve 46 35 will be equalized causing it to close.

While the piston 26 is making this movement, the steam in the cylinder 28 ahead of the piston exhausts through port 74, passage 50 and pipe 41. As the piston 26 approaches its extreme forward position, it closes the port 74 trapping the exhaust steam in the remaining portion 45 of the cylinder from which it slowly escapes through the bleed port 52, thus, an effective cushion is provided for the piston 26 at the end of its stroke.

By manipulating the previously referred to operating valve (not shown), the direction of the piston 26 is reversed by admitting steam into the cylinder through the pipe 41 and exhausting steam through pipe 40. Admission of steam to the front of the piston 26 is effected in the same manner as described above in connection with admission of steam to the rear of the piston 26 and exhausting of steam from the rear of the piston 26 is effected in the same manner as described above in connection with exhausting of steam from the forward end of the piston 26. It will be apparent, therefore, that a cushion is also provided for the piston on its rearward stroke when it closes the port 73, the trapped steam 60 escaping slowly through bleed port 53.

70 From the foregoing description, it will be evident that I have provided a simple and efficient coal pusher in which the pusher heads are capable of operating over a greater area of the slope sheet than in previous constructions without moving the motor a corresponding distance rearward and upward. At the same time, the piston rod of the motor is protected from contact with the coal in the bin on the forward 75 stroke of the pusher member.

I claim:

1. In a bin having a material supporting surface, a pusher device having a motor rigidly mounted on said surface and including a cylinder provided with a reciprocating piston and piston rod, a pusher head operatively connected with said piston rod for reciprocating movement over said surface, said pusher head being provided with an inverted U-shaped hood movable with said pusher head adapted to form with said supporting surface a shield for said piston rod when said piston is moved toward the forward end of said cylinder and to fit closely about the top and sides of said cylinder when said piston is moved toward the rearward end of the cylinder, the sides of said hood extending downwardly to said supporting surface throughout the travel of said hood, and cooperating means associated with said hood and supporting surface closely adjacent the sides of said cylinder forming a guide defining the path of movement of said hood.

2. A pushing device having a rigidly mounted motor including a cylinder provided with a reciprocating piston and piston rod, and a pusher head operatively connected with said piston rod,

5 a hood movable in concert with said pusher head adapted to form a shield for said piston rod when said piston is moved toward the forward end of said cylinder and to fit closely about the top and sides of said cylinder when said piston is moved toward the rearward end of the cylinder, the portion of said hood projecting forward of the cylinder to said pusher head when said piston is in its rearmost position being tapered, and 10 a removable cover in the top of said tapered portion of the hood providing access to the connection between said pusher head and piston rod.

EUGENE MARTIN.
